UNITED STATES PATENT OFFICE.

HENRY F. BECHMAN, OF BATTLE CREEK, MICHIGAN, ASSIGNOR TO DUPLEX PRINTING PRESS COMPANY, OF BATTLE CREEK, MICHIGAN.

INKING APPARATUS FOR PRINTING-PRESSES.

No. 823,098.

Specification of Letters Patent.

Patented June 12, 1906.

Application filed June 17, 1905. Serial No. 265,720.

To all whom it may concern:

Be it known that I, HENRY F. BECHMAN, of Battle Creek, in the county of Calhoun and State of Michigan, have invented certain new and useful Improvements in Inking Apparatus for Printing-PresSES; and I hereby declare that the following is a full, clear, and exact description thereof, reference being had to the accompanying drawings, which form part of this specification.

This invention is an improved inking apparatus for rotary cylinder printing-presses; and its objects are to enable the distributing-rollers to be thrown into or out of operative position at will and when thrown out of operative position to be moved so far away from their operative positions that they can be washed without removing them from their bearings; also, to have the form and co-acting distributing rollers capable of being similarly shifted; further, to have the two sets of rollers so connected that both sets are simultaneously shifted, the supports for one set of rollers operating the supports for the other set; also, to enable any or all of the rollers to be removed from or adjusted in the apparatus without the operator having to get into or under the machine, and to enable the printing surfaces or plates to be attached to or detached from the cylinders without removing any of the inking-rollers.

In the accompanying drawings, Figure 1 is a partly-broken side elevation of the complete inking apparatus. Fig. 2 is an end view thereof, and Fig. 3 is a detail. Fig. 4 is a vertical section on line 4-4, Fig. 2.

A designates a rotary plate cylinder of a rotary printing-machine, suitably journaled in bearings on the main frame B, which may be of any suitable construction. Below the axis of said cylinder and at the outer side thereof are form-rollers 1 and 1^a, which are adapted to supply ink to the plates on the cylinder. Roller 1 receives ink directly from a distributing-drum 2, journaled in the frame below cylinder A. Roller 1^a receives ink from the drum through the intermediates 2^a 2^b, the former of which contacts with the drum. The several rollers 1 1^a 2^a 2^b are mounted in suitable journals or hangers of ordinary construction attached to brackets 4, which are provided with tongues 4^a, engaging corresponding guide-slots in the adjacent portions of the side frames, as shown in Figs. 2 and 3, so that by sliding brackets

4 the set of rollers 1 1^a 2^a 2^b can be moved to or from the cylinder A. Brackets 4 are geared to the supports of the lower set of distributing-rollers, as hereinafter explained.

Below the drum 2 and adapted to contact therewith and distribute ink thereon are the vibrating or distributing rollers 5 5^a 5^b, which are mounted in suitable bearings of ordinary construction attached to swinging brackets or hangers 8, which are roughly segmental shaped and are suspended or swung from pivots 8^a, attached to the side frames above and exterior to the axis of the drum 2, so that if hangers 8 are swung outward the rollers 5 5^a 5^b will be swung outward and away from the periphery of drum 2, the axis on which the rollers swing being of greater radius than the drum. The lower parts of hangers 8 are toothed, as at 8^b, and mesh with pinions 9^a on a shaft 9, journaled in the frame below the hangers, and said shaft can be rotated by a hand-wheel or crank, (not shown,) so as to swing the hangers and move the rollers into or out of operative position.

Ink is supplied to drum 2 by a ductor 6, which is mounted on arms 6^a, attached to a shaft 6^b, journaled in the hangers 8, the ductor receiving ink from a supply-roll 7, journaled on the hangers 8, as shown, and adapted to contact with the roll 10^a of an ink-fountain 10, mounted in the main frame below the hangers, as shown. Roller 7 only contacts with the fountain-roll 10^a when the hangers are swung inward, and rolls 5 5^a 5^b are in contact with drum 2.

When the hangers are in their inmost position, an arm 6^c on shaft 6^b engages with a cam 6^d, which is operated by suitable gearing of any suitable construction, as indicated in dotted lines, Fig. 1, so as to vibrate ductor 6 in proper time between drum 2 and roller 7; but when the hangers 8 are swung outward the arm 6^c is moved away from the cam so the ductor will be idle. It will be noted that the rollers 5, 5^a, 5^b, 6, and 7 are all supported bodily on the hangers 8 and move therewith. Attached to the upper or pivot ends of the hangers 8 are gears 8^c, which mesh with pinions 4^c, engaging racks 4^b on the under sides of sliding brackets 4. Consequently when hangers 8 are swung outward to separate the rollers from drum 2 the bracket-slides 4 are simultaneously moved outward to separate rollers 1 1^a from the cylinder A. The position of the parts when thus moved outward

is clearly indicated by the dotted lines in Fig. 1.

Drum 2 may be driven from the cylinder by means of gears 2^c A² and intermediate 2^d.

I do not, however, herein claim the particular gearing for driving the drum nor the ductor cam-shaft.

With the described arrangement of parts it will be seen that the two sets of rollers (1 1^a to 2^a 2^b and 5 5^a 5^b 6 7) can be simultaneously moved into or out of operative position at one operation; also, that all the rollers, including the ductor, can be thrown in and out of working positions without affecting their relative adjustment; also, that when thrown fully outward they can be removed and replaced without going into or under the press, and that in such position they can be wiped or cleaned without removing them from their bearings, and the printing plates or surfaces can be put in or removed from the machine without removing any of the rollers.

The invention is obviously not restricted to the specific number and arrangement of rollers shown in the drawings, for more or less rollers may be mounted in the slides 4 or hangers 8, or both, according to the degree of distribution of ink desired.

Having thus described my invention, what I claim, and desire to secure by Letters Patent, is—

1. In combination with a rotary printing-cylinder, and a set of form-inking rollers mounted in movable supports; a distributing-surface, a set of distributing-rollers coacting therewith mounted in movable supports, and connections between the supports of said sets of rollers, whereby both sets of supports may be simultaneously moved to shift the rollers thereon into or out of operative position.

2. In combination with a rotary printing-cylinder, a rotary ink-drum, slides beside the cylinder, and form-inking and supply rollers mounted in said slides, and movable thereby simultaneously into and out of operative position of contact with the drum and cylinder, substantially as described.

3. In combination with an ink-distributing drum, a set of distributing-rollers, and a ductor-roller; with movable supports carrying all said rolls and adapted to move them to and from the drum, for the purpose and substantially as described.

4. In combination with an ink-drum, movable supports beside the drum, a set of distributing-rollers mounted in said supports, a ductor-roller mounted in said supports, means for moving said supports to move the rollers to and from the drum, and means for actuating the ductor when the rollers are in operative position.

5. In combination with an ink-drum, swinging hangers beside the drum, a set of distributing-rollers, a vibrating ductor-roller, and a

supply-roller mounted on said hangers, means for moving said hangers to move the rollers to and from the drum, and means for actuating the vibrator when the rollers are in their operative position.

6. In combination, a set of form-inking rollers, slides upon which said rollers are journaled; a set of ink-distributing rollers, swinging hangers supporting said distributing-rollers, and gearing between said hangers and slides whereby both sets of rollers may be simultaneously moved.

7. In combination, a rotary distributing-drum, a set of distributing-rollers coacting therewith, a ductor-roller and movable supports for all said rollers; with a set of form-rollers receiving ink from said drum, slides upon which said form-rollers are journaled, and gearing between the movable supports and said slides whereby both sets of rollers are simultaneously moved into or out of operative position, substantially as described.

8. In combination, a rotary distributing-drum, a set of distributing-rollers coacting therewith, a ductor-roller, and a supply-roller; and swinging hangers carrying all said rollers; with a set of form-rollers receiving ink from said drum, slides carrying said form-rollers, and gearing between the hangers and said slides whereby both sets of rollers are simultaneously moved, substantially as described.

9. The combination of an ink-fountain, an ink-supply roller, a rotary ink-distributing drum and a ductor for transferring ink from the supply-roller to the drum; with swinging hangers beside the drum, and distributing-rollers mounted in said hangers, and movable thereby to and from said drum, for the purpose and substantially as described.

10. In combination, an ink-distributing drum, with a set of distributing-rollers, a supply-roll, a ductor-roller, and a single set of swinging hangers carrying all said rollers, for the purpose and substantially as described.

11. In combination, a set of form-inking rollers, slides supporting said rollers; an ink-drum, a set of ink-distributing rollers, movable supports for said distributing-rollers, a supply-roller mounted on said supports, a ductor-roller for conveying ink from the supply-roller to the drum; and connections between said slides and supports whereby said slides and said supports may be simultaneously moved to throw the form-inking rollers and distributing-rollers into or out of operative position, substantially as described.

In testimony that I claim the foregoing as my own I affix my signature in presence of two witnesses.

HENRY F. BECHMAN.

In presence of —

GUY H. FENN,
CHARLES A. GRAMES.
